Primary Examiner — Ian Simmons*Assistant Examiner* — Charles Hanson(74) *Attorney, Agent, or Firm* — Myers Bigel Sibley &
Sajovec, P.A.**(57) CLAIM**The ornamental design for a dose disk for a dry powder
inhaler, as shown and described.**DESCRIPTION**FIG. 1 is a top perspective view of a dose disk for a dry powder
inhaler showing our design;

FIG. 2 is a top view thereof;

FIG. 3 is a side view thereof (for clarity it is noted that all side
and end views are the same when taken with the disk in the
same orientation); and,

FIG. 4 is a bottom view thereof.

The broken lines shown herein are for illustrative purposes
only and form no part of the claimed design.**1 Claim, 3 Drawing Sheets**# US D685,461 S

UNITED STATES PATENT AND TRADEMARK OFFICE
CERTIFICATE OF CORRECTION

PATENT NO. : D685,461 S
APPLICATION NO. : 29/385525
DATED : July 2, 2013
INVENTOR(S) : Striebig et al.

Page 1 of 1

It is certified that error appears in the above-identified patent and that said Letters Patent is hereby corrected as shown below:

On the Title Page, Item (54), and in the Specification, Column 1, Line 1, Title,

Please correct: "**DOSE DISK FOR A DRY POWDER INHALER**"

to read -- **DOSE DISK FOR DRY POWDER INHALERS** --

Signed and Sealed this
Fifth Day of November, 2013

Teresa Stanek Rea
Deputy Director of the United States Patent and Trademark Office
